UNITED STATES PATENT OFFICE

125,602

DESIGN FOR A GOLF CLUB HANDLE GRIP

William E. Wheeler, Philadelphia, Pa., and Martin Dietz, Brooklyn, N. Y., and Dorothy Greig Wheeler, Philadelphia, Pa.

Application October 2, 1940, Serial No. 95,584

Term of patent 14 years

To all whom it may concern:

Be it known that we, William E. Wheeler and Martin Dietz, both citizens of the United States and residing respectively, in the city and county of Philadelphia, State of Pennsylvania, and the Borough of Brooklyn, city of New York, county of Kings, State of New York, and Dorothy Greig Wheeler, a citizen of Canada and residing in the city and county of Philadelphia, State of Pennsylvania, have invented a new, original, and ornamental Design for a Golf Club Handle Grip, of which the following is a specification, reference being had to the accompanying drawing, forming part thereof, wherein—

Fig. 1 is a front view of a golf club handle grip showing our new design.

Fig. 2 is a rear view thereof.

Fig. 3 is a right side view of Fig. 1.

Fig. 4 is a left side view of Fig. 1.

We claim:

The ornamental design for a golf club handle grip, substantially as shown.

WILLIAM E. WHEELER.
MARTIN DIETZ.
DOROTHY GREIG WHEELER.
